Primary Examiner — Cynthia Ramirez*(74) Attorney, Agent, or Firm* — Armstrong Teasdale LLP(57) **CLAIM**

We claim the ornamental design for a conveyor frame, as shown and described.

DESCRIPTION

FIG. 1 is a top perspective view of a conveyor frame showing the new design.

FIG. 2 is another top perspective view of the conveyor frame of FIG. 1.

FIG. 3 is another top perspective view of the conveyor frame of FIG. 1.

FIG. 4 is another top perspective view of the conveyor frame of FIG. 1.

FIG. 5 is a bottom perspective view of the conveyor frame of FIG. 1.

FIG. 6 is another bottom perspective view of the conveyor frame of FIG. 1.

FIG. 7 is right side view of the conveyor frame of FIG. 1.

FIG. 8 is a left side view of the conveyor frame of FIG. 1.

FIG. 9 is a front view of the conveyor frame of FIG. 1.

FIG. 10 is a rear view of the conveyor frame of FIG. 1.

FIG. 11 is a top view of the conveyor frame of FIG. 1; and, FIG. 12 is a bottom view of the conveyor frame of FIG. 1. The broken lines in the figures show portions of the conveyor frame, which form no part of the claimed design.
